UNITED STATES PATENT OFFICE

163,313

PORTABLE VANITY MAKE-UP KIT

James Neal, Sr., Detroit, Mich.

Application June 25, 1949, Serial No. 3,540

Term of patent 3½ years

(CL. D86—10)

To all whom it may concern:

Be it known that I, James Neal, Sr., a citizen of the United States, residing at Detroit, in the county of Wayne and State of Michigan, have invented a new, original, and ornamental Design for a Portable Vanity Make-Up Kit of which the following is a specification, reference being had to the accompanying drawing, forming part thereof, in which:

Fig. 1 is a front elevational view of the portable vanity make-up kit as opened, showing my new design.

Fig. 2 is a right side elevational view thereof partially broken away for illustration; and

Fig. 3 is a perspective view of the portable vanity make-up kit.

Fig. 4 is a perspective view of the vanity make-up kit shown in Fig. 1, but on a larger scale.

The side of the make-up kit not shown is identical with that shown in Figure 2. The back of the opened vanity kit not apparent in Fig. 1 is plain, as partially shown in Fig. 3.

I claim:

The ornamental design for a portable vanity make-up kit, substantially as shown and described.

JAMES NEAL, SR.
